[57] CLAIM

The ornamental design for a stethoscope identification tag, as shown and described.

DESCRIPTION

FIG. 1 is a perspective view of a stethoscope identification tag showing a first embodiment of my new design, illustrating the same in a closed position and with the broken line showing for illustrative purposes only and forming no part of the claimed design;

FIG. 2 is another perspective view thereof, illustrating the same in an open position;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a front perspective view of a stethoscope identification tag showing a second embodiment of my new design, illustrating the same in a closed position;

FIG. 9 is another perspective view thereof, illustrating the same in an open position;

FIG. 10 is a front elevational view thereof;

FIG. 11 is a right side elevational view thereof;

FIG. 12 is a rear elevational view thereof;

FIG. 13 is a top plan view thereof; and,

FIG. 14 is a bottom plan view thereof.
